REST FOR ELECTRIC IRONS

Herbert W. Wilson, North Canton, Ohio, assignor
to The Hoover Company, North Canton, Ohio,
a corporation of Ohio

Application June 3, 1949, Serial No. 96,921

4 Claims. (Cl. 38—79)

1

This invention relates to electric pressing irons and more particularly to means for supporting the iron in a rest position and forming the means to expose the rear of the sole plate when the latter is used for pressing materials.

An object of the invention is to provide a new and improved iron. A further object is to provide an iron having the heel of the sole plate arcuately shaped and terminating in pointed ends for pressing, for example, shirt neckbands and frilled material. Another object is to provide means for supporting the iron in upended rest position, the means being bowed inwardly toward the iron body to expose the heel of the sole plate whereby the latter is visible to the operator when pressing material. A further object is to provide means for supporting an iron in a side rest position or upended rest position, the means also cooling the handle. Other objects and advantages of the invention will be apparent from the following description and drawings wherein:

Figure 1 is a top view of one embodiment of the invention;

Figure 2 is a side view with parts broken away;

Figure 3 is a top view of another embodiment of the invention; and

Figure 4 is a side view thereof with parts broken away.

The embodiment of the invention disclosed in Figures 1 and 2 comprises a sole plate 10, cover shell 11 and handle 12 the latter being attached to the shell 11 by a front bracket 13 and screws 14—14 and a rear bracket 15 having screws 16—16. The shell 11 is secured to the sole plate 10 by a screw 17 threaded into a stud 18 mounted on the sole plate, and by another screw 19 threaded into a bracket 20 which is suitably attached to the sole plate. A temperature control dial 21 is disposed between the handle legs to adjust an unshown thermostat which varies the ironing temperature of the sole plate 10.

The sole plate 10 is provided with a pointed front end 23 and two side walls 24 and 25 which terminate in points 26 and 27 respectively of a heel 28. Extending from the points 26 and 27 of the heel 28 is a wall 29 which is bowed inwardly and inclined upwardly as indicated at 30 to provide an arcuate end for pressing, as an example, the neckbands and armpits of a shirt. The pointed ends 26 and 27 are useful, for example, in pressing frills and gathered materials.

The rear end of the cover shell 11 is provided with an arcuate end 35 terminating in iron rest supports 36—36 which project beyond the arcu-

2

ate heel 29 and are offset with respect to the pointed ends 26 and 27 of the sole plate 10, and the arcuate end 35 is bowed inwardly of the arcuate heel 29 to expose the latter to the view of the operator. At the rear end of the handle 12 is a support 38 which cooperates with the rests 36—36 on the cover shell 11 to support the iron thereon when upended to its rest position on a surface 39, shown in dotted lines in Figure 2, whereby the corners 26 and 27 of the sole plate are spaced from the supporting surface 39.

When it is desired to press, for example, the neckband of a man's shirt, the arcuate heel 29 is of advantage because of its bowed configuration, and the arcuate heel 29 is visible to the operator since the arcuate portion 35 of the cover shell 11 is bowed inwardly of the sole plate. The projecting iron rests 36—36 are offset with respect to the pointed ends 26 and 27 of the sole plate and thus do not interfere with the operator's line of vision when ironing with the pointed ends 26 and 27.

The embodiment of the invention disclosed in Figures 3 and 4 comprises a sole plate 40 provided with a pointed end 41 and side walls 42 and 43 terminating in a heel 44 having an inclined inwardly concave surface 45 terminating in pointed ends or corners 46 and 47. A cover shell 48 is attached to the sole plate 40 by screws 49 and 50 threaded respectively into a stud 51 and bracket 52. A handle 53 is mounted on the shell 48 by a pair of brackets 54 and 55.

The cover shell 48 has a substantially straight rear end wall 56 terminating short of the arcuate surface 45 of the sole plate 40 and is also provided with a marginal recessed portion 57 spaced upwardly from the sole plate 40 to receive therebetween a combined iron rest and cooling member 58. The member 58 is mounted on the sole plate 40 by three studs 59, and has a plurality of tongues 60 welded to the cover shell 48 so that the latter and the member 58 are assembled as a unit to the sole plate 40. The rear end 61 of the member 58 is of arcuate contour and is disposed inwardly of the arcuate heel 45 to expose the latter to the operator's line of vision for ironing with the arcuate heel 45. A pair of rear rest supports 62—62 are formed on the member 58 and project beyond the arcuate heel 45 for cooperation with the rear end 63 of the handle to support the iron thereon in upended rest position on a supporting surface 64, indicated by dotted lines in Figure 4, whereby the pointed ends 46 and 47 of the sole plate are spaced from the surface 64.

Formed integrally with the member 58 are laterally extending side rest members 66 and 67 either of which cooperate with the sides 68-68 of the handle 53 to support the iron thereon in side rest positions.

A plurality of openings 70 are formed in the member 58 to aid in reducing the temperature of the latter. The tongues 60 space the member 58 from the defining edge 57 of the cover shell 43 so that air can circulate above the member 58 and below the shell 43 to cool the latter and thus the handle, and the studs 59 space the member 59 from the sole plate 40 for additional air circulation therebetween to aid in cooling the member 58.

When it is desired to press, for example, neckbands and armpits of men's shirts, the arcuate heel 45 is used and the latter is visible to the operator since the bowed portion 61 of the member 58 does not obstruct the concaved heel 45, nor do the rest supports 62-62 interfere with the operator's line of vision when the corners 46 and 47 are used to press frills or the like.

If it is desired to place the iron in a rest position the operator has three selections; by placing the iron in upended rear rest position the supports 62-62 and the rest 63 are arranged on the supporting surface 64, or by tilting the iron away from the operator the iron is supported on the rest member 67 and the adjacent edge 68 of the handle, and finally by tilting the iron toward the operator the iron is supported on the side rest 66 and the adjacent edge 68 of the handle.

I claim:

1. An electric iron comprising a body having a sole plate, a handle attached to said body and having an iron rest, said sole plate having opposed side walls terminating in an end wall, said end wall having a portion concaved toward said body and forming with the adjacent ends of each of said side walls a pointed end, means on said body disposed above said sole plate and having an end concaved toward said body and lying within the limits of said end wall to expose said concaved portion of said sole plate when viewed from above, said means terminating at its opposite ends in iron rest means cooperating with said handle rest to support said iron when the latter is upended into iron rest position, said iron rest means being offset inwardly of said body with respect to said pointed ends whereby said rest means do not interfere with the operator's line of vision when ironing with said pointed ends and said concaved end wall.

2. An electric iron comprising a body having a

sole plate, a handle attached to said body and having an iron rest, said sole plate having a heel bowed inwardly toward said body and forming two pointed ends, a pair of spaced rest members on said body projecting beyond said bowed portion of said heel above said sole plate and cooperating with said handle rest to support said iron when the latter is upended into rest position, and said spaced rest members being offset with respect to said pointed ends and spaced from each other to expose the bowed heel whereby said spaced rest members do not interfere with the operator's line of vision when ironing with said pointed ends and said bowed sole plate.

3. An electric iron comprising a body having a sole plate, a handle attached to said body and having an iron rest, said sole plate having a heel bowed inwardly toward said body for pressing material, and iron rest means on said body above said heel and cooperating with said handle rest to support said iron when upended into iron rest position, said iron rest means being concaved toward said body inwardly of said heel to expose said heel whereby said rest means does not interfere with the operator's line of vision when ironing with said heel.

4. An electric iron comprising a body having a sole plate, a handle attached to said body and having an iron rest, said sole plate having a heel end terminating in spaced pointed ends for pressing material, a cooling vane on said body and spaced from said sole plate to form an air passageway therebetween, said cooling vane having a portion terminating short of said heel to expose the latter when viewed from above, said cooling vane portion terminating at its opposite ends in iron rest means cooperating with said handle rest to support said iron when the latter is upended into rest position, said rest means on said cooling vane being offset with respect to said pointed ends of said heel to expose the pointed ends whereby said iron rest means do not interfere with the operator's line of vision when ironing with said heel and said pointed ends.

HERBERT W. WILSON.
